his Attorney in fact.

UNITED STATES PATENT OFFICE.

WILLIAM E. SKINNER, OF MILFORD, MICH., ASSIGNOR OF TWO-THIRDS HIS
RIGHT TO GEO. D. AUSTIN AND QUINCY MATTHEWS, OF SAME PLACE.

IMPROVEMENT IN BEVEL-GAGES.

Specification forming part of Letters Patent No. 154,526, dated August 25, 1874; application filed
May 5, 1873.

To all whom it may concern:

Be it known that I, WILLIAM E. SKINNER, of Milford, county of Oakland and State of Michigan, have invented an Improved Bevel-Gage.

The following description, taken in connection with the accompanying plate of drawings hereinafter referred to, forms a full and exact specification, wherein are set forth the nature and principles of the invention, by which the same may be distinguished from others of a similar class, together with such parts thereof as are claimed as new, and are desired to be secured by Letters Patent of the United States.

My invention consists in an attachment to carpenters' bevel-squares, whereby the blade or tongue of the same can be adjusted and set to any desired angle and securely fixed there; said attachment consisting of a quadrant divided on its face into the degrees of a quarter-circle, fastened to the stock of a bevel-square by means of a stationary hinge, and sliding and turning upon the same.

In describing, I refer to the annexed drawings making part of this specification, and illustrating my invention more fully.

Figure 1 represents my invention in a perspective view. Fig. 2 is a top view of my invention attached to a bevel-square. Fig. 3 is an end view of the same.

Like letters of reference in the several figures indicate like parts.

A is a metallic plate, its shape being that of a quarter-section of a ring. It is provided on its face with a number of divisions, A¹, on both its circular edges, said divisions being the degrees of a quadrant, and having a common center wherefrom they radiate. The face of the plate A is also provided with a number of lines, A², and two rows of numerals, A³, directly between and corresponding with lines A². The dial-plate A is bent on one edge to a double right angle, and there provided with two hinges, B B. C is a stationary hinge-plate. It is fastened to the stock of a bevel-square, and provided with a stationary pivot, D, whereupon the dial-plate A is sliding and

turning. E is the stock of a common bevel-square, and F the tongue or blade of the same. G is a thumb-screw, fastening tongue F within the stock E.

It will be observed that the dial-plate A is movable upon the pivot D, and that it is sliding upon the same. This is rendered necessary, from the fact that the point of intersection of all the divisions upon plate A and the blade or tongue F varies according to the number of degrees of the angle indicated between them. It will also be observed that, besides the degrees of a circle, the face of the dial-plate A is provided with eight lines on each end of the circular part of plate A, marked A², and with two rows of numerals directly below the lines A², marked A³. Their purpose is to enable a carpenter to set the bevel-square to any desired inclination or pitch of a roof for buildings, and at the same time give ready means for calculating the proper length for the rafters for said building, the lines A² and the first row of numerals, A³, indicating what is known to carpenters as one-eighth, one-sixth, one-fifth, one-fourth, one-third, one-half, two-thirds, and three-fourths pitch, and the second row of numerals, directly below and corresponding with those of the first row, designating that for every foot of half the width of a building, three-eighths, or five-eighths, or seven-eighths, or one and three-eighths, or two and three-eighths, or five, or eight, or nine and five-eighths inches are to be added to that number to give the proper length of the rafter of the building; as, for example, suppose a building to be twenty-four feet wide and of one-eighth pitch of the roof, then $24 \div 2 = 12 \times \frac{3}{8} + 12 = 12$ feet $4\frac{1}{2}$ inches, the proper length of the rafter.

In order to set the tongue of the bevel-square to any desired angle, it is only necessary to slide the plate A up and down and turn the blade or tongue F until its edge coincides with the divisions or degrees on both edges of the circular part of A, when the same will be set to the desired angle, and can be securely held there by means of the thumb-

screw G. The object of sliding the dial-plate, as described, is to adjust the same so that the radial divisions on its face may be brought to coincide with the face of the blade or tongue F at the points required. This adjustment is rendered necessary on account of the face of the blade being used while the blade is pivoted on the thumb-screw G, passing through the center of the blade F.

When the blade F has been adjusted by means of the dial-plate A, the said dial-plate may be swung backward, as indicated in dotted lines in Fig. 3, when it will be entirely out of the way, and the bevel-square ready for use.

I prefer to make my improved attachment of sheet metal, and stamping the divisions and figures upon the same; but it may be also made in various other ways.

Having thus fully described my invention, so as to enable any one skilled in the art to which it pertains to make or use the same, I desire to secure by Letters Patent—

In combination with a bevel-square having an adjustable tongue, the movable and adjustable plate A, provided on its face and both its circular edges with indentations or marks corresponding to the degrees of a quarter of a circle, and fastened to the stock E by means of the stationary hinge-part C and pivot D, substantially as described.

WILLIAM E. SKINNER.
